COLLAPSIBLE POCKET HANGER FOR COATS
AND HATS

Maurice Levey, Yonkers, N. Y.

Application January 24, 1948, Serial No. 4,165

2 Claims. (Cl. 211—104)

1

This invention relates to hangers for articles such as hats and coats.

More particularly, the invention aims to provide new and useful improvements in collapsible hangers of the kind to be carried personally for use whenever and wherever desired, as by being temporarily attached to a wall, or, for outdoor use, to a fence board, a post, a tree or the like.

A particular object of the invention is to provide a portable hanger so constructed that the same is collapsible to such small bulk, while so light in weight, as to permit it to be carried even in a vest pocket or in a small purse, yet a hanger which, conveniently and instantaneously attachable to and detachable from a selected support, may be extended for having suspended therefrom a plurality of fairly heavy articles.

Another particular object of the invention is to provide a hanger as above which consists solely of a unitary scabbard member, a unitary auxiliary member slidably and rockably movable relative to the scabbard member, and a prong means or equivalent for insertion into a selected support to position the scabbard member so that the auxiliary member, after being endwise partially withdrawn from the scabbard member, may be rocked through substantially 90° to extend the auxiliary member as an arm offset from the scabbard member.

Another particular object of the invention is to provide a scabbard member, below called the scabbard, which is so constituted that by simple die means it may be stamped from sheet stock with substantially no waste of material, and an auxiliary member, below called the arm, also so constituted that by simple die means it may be stamped from sheet stock with substantially no waste of material.

According to the invention, said scabbard and said arm are so formed that a bottom portion of the scabbard, which when the device is expanded is usable as a hanger element additional to the extended arm, acts also as a stop for limiting a sliding movement of the arm to be made to collapse the hanger.

Also according to the invention, there is provided in a collapsible hanger wherein an arm is rockable relative to a scabbard to extend the arm, an interaction between these two members such that a hinge means therebetween of the pin or pintle including type is dispensed with, thereby to eliminate from the total manufacturing cost any allowance for assembly expense.

In the connection last mentioned, guide-rail and trackway elements are provided, the guide-

2

rail on the arm and the trackway on the scabbard, for coacting with the arm in its sliding movements relative to the scabbard and for restraining the arm against shift thereof laterally of the scabbard when the arm is extended, in combination with inter-hooking parts and mutually abutting parts on the scabbard and on the arm so arranged that after the lower end of the arm has been slid upward to arrive near the top of the scabbard, the arm may be swung down for substantially horizontal projection away from the scabbard and for then being halted so projected.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of a now favored embodiment of the invention, collapsed.

Fig. 2 shows the collapsed hanger in front elevation.

Fig. 3 is a rear elevation thereof.

Fig. 4 is a view similar to Fig. 1, but showing the hanger mounted on a suitable support and with the arm extended.

Fig. 5 is a perspective view of the scabbard.

Fig. 6 is a perspective view of the arm.

Fig. 7 is a top plan view of the arm.

Fig. 8 is a fragmentary rear elevation thereof, looking in the direction of the arrow 8 of Fig. 7.

Referring to the drawing in detail, the scabbard as a whole is marked 10, and the arm as a whole is marked 11.

The scabbard 10, which may be stamped from sheet metal, incorporates a back wall 12, two side walls 14 and 15, and two front wall flanges 16 and 17 having free side edges spaced to provide a trackway 18. Above the side walls 14 and 15 the back wall 12 is forwardly curled or bent to present a transverse hook or lip 19, while the back wall below said side walls is forwardly curled to present a larger transverse hook 20.

The arm 11, which also may be stamped from sheet metal, comprises a main portion 21 of plate form, below which portion 21 the arm is curled or bent to present a transverse hook or lip means 22. Above the portion 21 the arm is curled to present a transverse hook 23.

A central longitudinal subdivision of the arm 11 is formed up, along three parallel lines of fold, to provide a U-type rib 24. This rib, extends down along said main portion 21 of the arm, to

have a bottom length 24^a of said rib in straight-line prolongation of the portion of the rib thereabove; the hook or lip means 22 having two cut outs as indicated at 25 and 26 in Fig. 3, to form the hook or lip means 22 as a pair of sidewise spaced hook or lip elements.

The hook 23 of the arm is strengthened by a prolongation 24^b of the rib 24; this rib portion 24^b being flared outwardly toward the free end of the hook 23.

Offset from and suitably secured to the rear side of the scabbard 10 is a prong 27, whereby the scabbard may be temporarily but dependably attached to a suitable support, such as indicated at 28, and then for extension of the arm 11 as shown in Fig. 4; whereupon a coat or the like may be suspended from the hook 20, and another garment or garments and/or a hat may be suspended from the arm.

When the device is collapsed as in Figs. 1-3, a suitable shield may be applied to the prong 27; such, for instance, as an ordinary cork 29, as one captive on a string or cord 30 attached to the hook 20, so that the shield 29 may dangle when the hanger is in use, as shown in Fig. 4, or placed on the prong as indicated in dot and dash lines at 29^a in Fig. 1 when the device is collapsed.

Assembly of the parts as in Figs. 1-3 is effected merely by sliding the arm 11 down all the way into the scabbard 10, until the bottom of the rib portion 24^a comes to rest against the hook 20. At the beginning of this sliding movement, with the arm 11 arranged so that its hooks or lips 22 and 23 face the back wall 12 of the scabbard, the main plate portion 21 of the arm moves down between the side walls 14 and 15 and between the back wall 20 and the front flanges 16-17 of the scabbard, and the parts are held against binding by the action of the rib 24 as a guide-rail relative to the trackway 18.

With the parts thus assembled, to extend the arm 11 as shown in Fig. 4 it is merely necessary to pull upward on the arm at its hook 23 until its bottom hooks or lips 22 engage the top hook or lip 19 of the scabbard, and then swing the arm down through 90° in a clockwise direction. Thereupon, as shown in Fig. 4, the lips 22 become interlocked with the lip 19, and the main plate portion 21 of the arm abuts the tops of the front flanges 16 and 17 of the scabbard, with the result that droop of the arm 11 from the horizontal is prevented. At the same time, the arm is held against lateral displacement from the scabbard, by retention of the portion 24^a of the rib 24 in the trackway 18.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A collapsible article hanger comprising a scabbard, an arm endwisely slideable in the scabbard for partial withdrawal therefrom to bring the lower end of the arm to the upper end of the scabbard, the lower end of the arm having a portion offset rearwardly in relation to the arm and the upper end of the scabbard having a por-

tion offset forwardly in relation to the scabbard, said offset portions being so shaped and arranged that they mutually engage when the arm has been upwardly withdrawn as above from the scabbard and become interlocked when thereafter the arm is swung down through substantially 90° relative to the scabbard, and stop means partially carried by the arm and partially carried by the scabbard for coacting with such interlocking to prevent droop of the arm relative to the scabbard, there being means including a guide-rail and a trackway, said means partially carried by the arm and partially carried by the scabbard for assisting to hold the arm to non-binding travel lengthwise of the scabbard, and there being a second stop means partially carried by the arm and partially carried by the scabbard for limiting downward sliding movement of the arm in the scabbard to prevent downward protrusion of the arm from the scabbard, said second stop means including the lower end of said guide rail and a hook portion on the bottom of the scabbard, said scabbard over the main portion of its length being of substantially C-shaped cross-section thereby to provide said trackway at the mouth of the C, said guide-rail being a rib-formation integrally carried by the arm, the first-named stop means including the top of said main length of the scabbard and a portion of the arm alongside said rib.

2. A collapsible article hanger comprising a scabbard, an arm endwisely slideable in the scabbard for partial withdrawal therefrom to bring the lower end of the arm to the upper end of the scabbard, the lower end of the arm having a portion offset rearwardly in relation to the arm and the upper end of the scabbard having a portion offset forwardly in relation to the scabbard, said offset portions being so shaped and arranged that they mutually engage when the arm has been upwardly withdrawn as above from the scabbard and become interlocked when thereafter the arm is swung down through substantially 90° relative to the scabbard, and stop means partially carried by the arm and partially carried by the scabbard for coacting with such interlocking to prevent droop of the arm relative to the scabbard, said mutually engaging and interlocking offset portions being oppositely facing lips, and said rib being so extended that at the conclusion of said partial upward withdrawal of the arm from the scabbard the bottom portion of the rib remains in the trackway, whereby incidental to said downswing of the arm, said bottom portion of the rib remains in coaction with the trackway to prevent lateral shift of the arm effective to disengage the arm from the scabbard while the arm is extended.
